UNITED STATES PATENT OFFICE.

CORWIN G. DEAN, OF WILDOMAR, CALIFORNIA, ASSIGNOR OF ONE-HALF TO JOHN G. DEAN, OF WILDOMAR, CALIFORNIA.

TOY TRACKLAYING TRACTOR.

Application filed August 20, 1924. Serial No. 733,126.

This invention relates to toys of the class known as pull toys adapted to be pulled by means of a string or the like or to be pushed by the hand and the chief object of the invention is to provide a toy of this character which is novel, amusing, and at the same time of strong and rugged construction, and is adapted to be pushed or pulled over rough or soft ground.

10 The accompanying drawings illustrate embodiments of my invention and referring thereto:

Fig. 1 is a plan view.

Fig. 2 is a partly sectional elevation.

15 Fig. 3 is a rear elevation.

Fig. 4 is a transverse vertical section through one of the wheels and the corresponding traction belt.

20 Fig. 5 is a section through adjacent elements of the traction belt on line 5—5 in Fig. 4.

Fig. 6 is a perspective of one of the elements of the traction belt.

25 My invention comprises a body or frame member 1 which may be provided with any suitable super-structure resembling that of a commercial tractor for example a hood portion indicated at 2 and a seat indicated at 3 mounted for example on a support 4 on the main body member 1. Wheels 5 may be mounted on shafts 6 extending through body member 1 near the front and rear ends thereof.

30 The novel feature of my invention comprises a traction belt adapted to extend over wheels 5 on each side of the device and to form an endless track upon which said wheels run. Said traction belt may comprise a plurality of traction elements 7, each of said elements comprising a flat central or web portion 8 adapted to engage the peripheries of the wheels 5 and having a flat traction surface 9 adapted to engage the ground or other surface over which the toy moves and inwardly projecting side portions 15, each adapted to engage the sides of wheels 5 so as to embrace the same and retain the belt in position on said wheels. As indicated in Figs. 3 and 4, I prefer to form the wheels with substantially vertical side faces and to incline the inner faces of the side portions 15 outwardly so as to minimize surface contact between said inner faces and the side faces of the wheels. Said elements 7 may be supported and

joined together by means of suitable supporting means, said supporting means for each element comprising for example a link consisting of a wire 10 bent in U-shape as indicated in Fig. 5. Each of 60 said connecting and supporting members thus comprises a transverse portion 11 at one end of an element 7 and lateral portions 12 with which said element engages in any suitable manner; for example said side portions may extend in grooves 13 at the respective sides of said elements. Said side portions of the connecting wires are further provided at their ends with hooks or eyes 14 adapted to flexibly engage the 70 portion 11 of the adjacent connecting means. The series of interconnecting U-shaped supporting members thus form in reality a chain or belt, upon which the traction elements 7 are supported, by engagement of 75 grooves 13 with the side portions of the connecting wires or in any other suitable manner. As shown, I prefer to mount a single traction element on each of the supporting links.

80 The above described toy may be made of any suitable material, for example, metal, although for simplicity of construction and in order to provide for necessary strength in conjunction with lightness I prefer to 85 make the body, superstructure, wheels and elements of the traction belt of wood, shaft 6 being of any suitable metal for example brass and the connecting wires 10 consisting of iron, steel or other wire. In order to 90 provide a good bearing for the wheels so as to facilitate the turning of the same I prefer to provide each wheel 5 with a metal sleeve or bearing 16 through which shaft 6 extends and suitable means may be provided for 95 retaining the wheels in position upon the shaft for example said shafts may be threaded at their ends as at 17 and provided with retaining nuts 18.

100 Suitable means such as a hook or eye 20 may be provided at the front end of the toy for attaching a string or other means by which the toy may be pulled.

105 In the operation of the toy, for example upon being pulled or pushed along the ground in the manner above described, the traction belt rides over the respective wheels and the portions of said belts which rest upon the ground underneath wheels 5 form a track upon which said wheels run. The 110

toy is thus adapted to run over soft ground and to easily pass over obstacles or rough places in the ground, thus making it well adapted for use at beaches or similar places.

5 It will be observed that, as distinguished from a full sized commercial tractor, there is no engagement between the wheels 5 and the traction belt composed of elements 7 other than by the friction of said elements 10 against the wheels, the peripheral surfaces of the wheels 5 being smooth, that is to say, free from projections. While such a construction would not be adapted for use in a large machine it provides a simple and at 15 the same time an effective means of operation in a toy.

What I claim is:

1. In a toy track-laying tractor, a body, shafts mounted on said body, wheels mounted 20 on said shafts in alignment with each other and having smooth peripheral surfaces and smooth vertical side faces, and a traction-belt extending over said wheels and comprising a plurality of traction elements 25 having flat portions adapted to engage said smooth peripheral surfaces and side portions adapted to extend over the sides of the wheels so as to embrace the same, said side portions having their inner faces inclined 30 outwardly so as to minimize surface contact between said inner faces and the side faces

of the wheels, and means for connecting said traction elements together.

2. A traction belt for toy tractors comprising a supporting chain composed of a plurality of flexibly interconnected links having lateral supporting members, and a single traction element corresponding to each of said links and having a flat traction surface and also having means engaging the supporting members on the corresponding link so as to be rigidly secured thereto.

3. In combination with a toy tractor provided with wheels having smooth peripheral surfaces, a traction belt adapted to extend over said wheels and comprising a plurality of U-shaped links, each provided with means flexibly engaging an adjacent link so as to form a supporting chain, and traction elements corresponding to said links and each comprising a web portion adapted to engage the peripheries of the wheels and having a traction surface, side portions adapted to extend over and engage the sides of the wheels, and grooves 55 adapted to receive the side portions of the U-shaped links so as to support said traction elements.

In testimony whereof I have hereunto subscribed my name this 12th day of August, 1924.

CORWIN G. DEAN.
